(57) CLAIM

The ornamental design for a treat maker and pill concealer, as shown and described.

DESCRIPTION

FIG. 1 is a top, front left side perspective view of a treat maker and pill concealer showing our new design.

FIG. 2 is a front elevational view thereof.

FIG. 3 is a rear elevational view thereof.

FIG. 4 is a right side elevational view, the left side elevational view being a mirror image thereof.

FIG. 5 is a top plan view thereof; and,
FIG. 6 is a bottom plan view thereof.

The broken lines in FIGS. 1 and 5 of the treat maker and pill concealer are for the purpose of illustrating environment, and form no part of the claimed design.

1 Claim, 3 Drawing Sheets

FIG. 1

FIG. 2
